DUPLICATING TOOL

Sherman L. Cook, Salem, Mass., assignor to The
Delta Manufacturing Company, Milwaukee,
Wis., a corporation of Wisconsin

Application July 7, 1933, Serial No. 679,337

6 Claims. (Cl. 142—38)

The invention relates to turning tools and more particularly to tools for duplicating wood turnings.

The duplication of turned pieces on a hand lathe has been a difficult and tedious undertaking requiring considerable skill, notwithstanding the aid of the usual templates which are applied to the work from time to time as the turning progresses.

An object of the present invention is to provide a simple but effective turning tool for a hand lathe by which turned pieces can be rapidly and accurately duplicated, even by unskilled persons, the tool being guided by a template having a profile which is reproduced in the finished work.

Another object of the invention is to perfect details of construction generally.

The invention further consists in the several features hereinafter described and claimed.

In the accompanying drawings,
20 Fig. 1 is a side elevation, partly in section, of a duplicating tool embodying the invention;

Fig. 2 is an end elevation of the tool;
25 Fig. 3 is a detail sectional view of a cutting element and guard therefor;

Fig. 4 is a detail sectional view taken along the line 4—4 of Fig. 1;
30 Fig. 5 is a detail view, partly in section, of a modified form of cutting member and guard;

Fig. 6 is a detail sectional view taken along the line 6—6 of Fig. 5;

Fig. 7 is a side elevation of a modified form of duplicating tool;

Fig. 8 is a sectional view taken along the line 8—8 of Fig. 7;

35 Fig. 9 is a side elevation of another modified form of duplicating tool, parts being broken away and parts being shown in section, and

Fig. 10 is a sectional view taken along the line 10—10 of Fig. 9.

40 In these drawings, the numeral 15 designates the bed of a wood-turning lathe. A flat horizontal table 16 is adjustably secured to the lathe bed by any suitable clamping means 17. A pair of spaced supports 18 are rigidly secured to the table, as by fastening elements 19, and have mounted thereon, as by fastening elements 20, a flat horizontal template or pattern 21, having an edge with a suitable profile which it is desired to duplicate in a turned piece 22 carried by the lathe.

45 In that form of the invention shown in Figs. 1 to 6, a cast metal base or shoe 23 is slidably mounted on the table 16 and is provided with a vertical bore 24 slidably receiving the lower end 50 of an upright cylindrical bar 25 which has its

upper portion cut away to form a semi-cylindrical open ended channel 26, the upper end of which is sharpened, as seen in Fig. 3, to present a cutting edge or nose 27. Upwardly projecting side ears 28 are here shown to be formed on the upper end of the channel. 5

The lower end of the bore 24 is closed by a disk 29 secured to the base by screws 30 and carrying a central vertical screw 31 abutting against the lower end of the bar 25 to adjust the vertical 10 position of the bar and thereby locate the cutting edge 27 substantially at the horizontal axial plane of the work. The bar 25 is clamped in position by a set screw 32 in the base and by another set screw 33 mounted in an angle shaped bracket 34 15 integrally formed on the base, the bracket having a bore 24' in which the bar slidably fits. The upper portion of the bracket 34 is spaced from the base, and the cylindrical portion of the bar 25 in the intervening space is adapted to slidably 20 bear against the profiled edge of the template 21.

A guard bracket 35 is secured by screws 36 to the upper surface of the base 23 and has a laterally projecting upper end provided with a cylindrical guard 37 which is aligned with the bar 25 25 and is spaced a short distance above the cutting edge 27. The cutting edge projects slightly beyond the lower edge of the guard 37 and is preferably given a slight flare or outward inclination for cutting clearance. 30

In use, the base 23 is slid about on the table 16 to bring the cutting edge 27 against the work 22, which in many cases may start as a blank of square cross-section. While the base is resting flat on the table, it may be swung to various positions to suit the work at hand. The guard 37, by its abutment with the work, limits the depth of cut so as to insure smooth and safe cutting. Eventually, the cylindrical bar 25 slidably abuts against the profiled edge of the template 21 to 40 limit the cutting movement of the tool, and to determine the profile of the finished work. Successive work pieces turned on the lathe in a similar manner will be accurate duplicates of the first. If the template 21 is shifted transversely 45 of the lathe bed between turning operations, the work pieces will have the same profile but will be of different diameters. In some instances, it is possible to use a turned piece as a template. 50

It will be obvious that the table 16 can be supported in other ways than that illustrated. In the case of a bench lathe, it will be apparent that the bench itself may form the support for the tool base 23.

55 For many classes of work it is desirable to pro-

vide a second tool, similar to the first, but having a bar 25' formed with cutting and guide portions 26' of V-shaped cross section, as seen in Figs. 5 and 6, to cut relatively sharp recesses in the work. The cutting edge 27' is given a slight flare, as seen in Fig. 5. The guard bracket 35' carries a guard 37' of V-shaped cross-section spaced a short distance above the cutting edge, and the cutting edge projects slightly beyond the guard.

In the form of the invention shown in Figs. 7 and 8, a slidable base or shoe 123 has secured thereto by screws 136 an upright bracket 135 having vertical slots 138 formed transversely therethrough near its opposite edges. A channel-shaped cutting member 125 with parallel sides embraces one edge portion of the bracket and is adjustably clamped thereto by bolts 139 passing through the lower slots 138. The opposite side edges of the cutting member are provided with inturned flanges 140 slidably fitting in vertical grooves 41 formed in the opposite faces of the bracket. The upper end of the cutting member is sharpened to form a slightly flared cutting edge 127 which is located substantially at the horizontal axial plane of the work. The upper side edges of the cutting member are formed with recesses 142 for the passage of chips.

A channel-shaped guard member 137 embraces the edge portion of the bracket above the cutting member 125 and is adjustably secured to the bracket by bolts 139 passing through the upper slot 138. A rounded depending portion of the guard member is spaced at a short distance above the cutting edge 127, and the cutting edge projects slightly beyond the guard member.

A channel-shaped cutting member 125' embraces the other edge portion of the bracket 136 and is adjustably secured to the bracket in the same manner as the cutting member 125. The cutting member 125' has a V-shaped outer edge 126' for cutting relatively sharp recesses in the work. A guard member 137' of similar cross-section is secured to the bracket 135 in the same way as the guard member 137.

The base 123 is preferably formed with recesses or notches 143 at opposite ends in register with the lower ends of the cutting members 125 and 125' to provide clearance for chips.

The device of Fig. 7 is used in the same way as the device of Fig. 1. The cutting member 125 is first applied to the work and then, if necessary the device is swung around to apply the V-shaped cutting member 125' to the work.

In the form of the invention shown in Figs. 9 and 10, a slidable base or shoe 223, has secured thereto by screws 236 a bracket 235 provided with a hollow polygonal standard 244. The bracket may be die cast and in some instances may be integral with the base. The bracket is provided at opposite ends with hollow posts 245 and 245' of triangular cross-section, the upper surface of each post sloping downwardly toward the standard. A channel-shaped cutting member 225 has diverging sides embracing the post 245 and is adjustably fixed thereto by a C-shaped clamp 246 secured to the post by a set screw 247, the converging ends of the clamp engaging the diverging sides of the cutting member. Recesses 248 are formed in the base, one of which is in register with the cutting member 225 to permit extended downward adjustment of this member. The upper end of the cutting member forms a rounded nose and is sharpened to provide a cutting edge 227. The lower portion of the cutting

member slidably abuts against the profiled edge of the template 21 near or below the clamp 246, the opening in the clamp 246 permitting an unobstructed view of the touching parts of the cutting member and template.

A die cast guard holder 248' is slidably but non-rotatably mounted on the standard 244 for vertical adjustment and is clamped in adjusted position by set screws 249, the guard holder having a sleeve portion 250 in which the standard slidably fits. Near its opposite ends, the guard holder has vertical bores 251 receiving bolts 252, one of which clamps a guard block 237 to the lower face of the holder, the guard block being spaced a short distance above the cutting edge 227. The nose of the guard block has the same shape as that of the cutting member, but the cutting edge 227 projects slightly beyond the guard block.

A channel-shaped cutting member 225' has flared sides embracing the other post 245' and is adjustably secured thereto in the same manner as the cutting member 225. The cutting member 225 has a V-shaped outer edge 126' for cutting relatively sharp recesses in the work. A guard block 237' of similar contour is secured to the holder 248 in the same manner as the guard block 137.

Each cutting member 225 and 225' can conveniently be formed for bending to shape a sheet of tool steel. The clamping means is of such character that no openings need be made in the cutting members.

The device of Fig. 9 is used in the same manner as the devices of Figs. 1 and 7, the cutting members 225 and 225' being successively applied to the work. The space between the flaring sides of each cutting member is open at the back above the supporting posts so as to permit free discharge of chips.

While the cutting surface and template-touching surface are preferably formed on the same member to secure accuracy, it will be obvious that they can be formed on separate members.

The tool may also be used for original work without the template, and can be operated with safety by unskilled persons.

What I claim as new and desire to secure by Letters Patent is:

1. A duplicating tool for a lathe, comprising a slidable base having an upstanding portion, a cutting member embracing said upstanding portion and having an upper cutting edge adapted to operate on a work piece, said cutting member and upstanding portion having relatively slidably interfitting tongue-and-groove parts at opposite sides for guiding the cutting member in a longitudinal adjustment, and means for clamping said cutting member to the upstanding portion, said cutting member having a template-touching surface for determining the profile of the work piece.

2. A duplicating tool for a lathe, comprising a slidable base having a post, a cutting member having diverging side walls fitting against said post and having an upper cutting edge adapted to operate on a work piece, a C-shaped clamp having spaced end portions engageable with said diverging walls to draw them against said post, and screw means at an intermediate portion of said clamp for displacing said clamp, said cutting member having a template-touching surface for determining the profile of the work piece.

3. A lathe tool comprising a movable base having a post and a standard, a vertically adjustable cutting member clamped to said post and having an upper cutting edge, and a vertically ad-

justable guard carried on said standard and having a guard portion spaced a short distance above the cutting edge to limit the depth of cut.

4. In a lathe, the combination, with a supporting member having a broad and flat upper surface parallel to the work axis of the lathe, of a base supported on said surface and being slidable and swingable thereon at will in any desired direction and orientation, and a cutting member carried by said base to operate on a rotatable work

10 piece driven by the lathe.

5. In a lathe having a bed, the combination of a plate detachably clamped to the lathe bed and having a broad and flat upper surface parallel to the work axis of the lathe, a base supported

15 on said surface and being slidable and swingable

thereon at will in any desired direction and orientation, and a cutting member carried by said base to operate on a rotatable work piece driven by the lathe.

6. In a lathe having a bed, the combination of a plate detachably clamped to the lathe bed and having a broad and flat upper surface parallel to the work axis of the lathe, a base supported on said surface and being slidable and swingable thereon at will in any desired direction and orientation, a cutting member carried by said base to operate on a rotatable work piece driven by the lathe, and a template carried by said plate for limiting the advance of the cutting member to the work piece.
